COLLAPSIBLE BOX

Frank Grasso, Wilkes-Barre, Pa.

Application March 30, 1932. Serial No. 602,081

8 Claims. (Cl. 150—49)

My invention relates to a collapsible receptacle of the type wherein a canvas hamper or bag is carried by a collapsible frame so that when the receptacle is not in use it can be flattened out and occupy very little space. In shipping garments from factory to factory, or from factory to dealer, it is more or less customary to place the garments in boxes or crates of rigid construction lined with canvas or other suitable material to protect the garments. These crates after delivery are rarely returned to the shipper as, owing to their bulk, the expense of shipping them back empty is considerable; so the crates are lost to the shipper.

My invention, therefore, has for an object to provide a collapsible crate-like structure of an improved construction which, when its contents have been removed, may be quickly collapsed and will thus occupy only a fraction of the space that it occupied when in use and thus insure the return of the receptacles to the shippers so that they may be used over and over again.

It is a further object of my invention to provide a ruggedly constructed receptacle which can be manufactured at low cost and which will be sufficiently strong not to be bent or warped out of shape or easily broken when in use.

Other objects of my invention will in part be obvious and in part be pointed out hereinafter. To the attainment of the aforesaid objects and ends, the invention still further resides in the novel details of construction, combination and arrangement of parts, all of which will be first fully described in the following detailed description, and then be particularly pointed out in the appended claims, reference being had to the accompanying drawing, in which:—

Figure 1 is a perspective view of my invention in use.

Figure 2 is an end view of the same, fully collapsed.

Figure 3 is an inverted plan of a portion of the bottom of the receptacle.

Figure 4 is a detail perspective view of a portion of the lid with its cover broken away.

Figure 5 is a detail perspective view of a portion of the upper edge of the front frame which cooperates with the part shown in Figure 4.

Figure 6 is a detail perspective view showing one of the lid hinge members.

In the drawing, in which like numerals of reference indicate like parts in all the figures, 1 represents the rectangular frame of the base portion of the receptacle. This is composed of

rod or wire and has secured to it a lattice-work composed of longitudinal slats 2 and transverse slats 3, the slats being riveted together as at 4 and looped around the rod 1 as at 5.

6 is the rectangular rod-like frame of the top 60 of the receptacle. It carries a pair of locking lips 8 which are looped around the rod 6 as at 7 and apertured as at 9 for the reception of a padlock.

10 are loops welded to the rod 6 and forming 65 hinge bearings for the lid.

The lid is composed of a rectangular frame 11 provided with longitudinal slats 12 and transverse slats 13 riveted together at 15 and looped around the rod 11 as at 14, thereby constituting 70 a lattice-work.

The lid frame carries a pair of locking bars 16 that are riveted at 17 to one of the longitudinal bars 12 and are passed over the front rod 11 and offset to form ears 18 that are apertured at 19 to 75 cooperate with the ears 8, the portions of the bars 16 which overlie the rod 11 being spot-welded or otherwise firmly secured to the rod.

The frame of the lid has its under face covered by a covering of fabric 20, the edges of which are 80 lapped over as at 21 and secured by sewing as at 22.

The rectangular rod-like base frame 1 and the rectangular rod-like top frame 6 are connected together front and back by front and back frames, 85 each of which comprises vertical rule-joint struts 23, the ends of which are looped at 24 around the rods 1 and 6 respectively. The rule-joints 25 are located midway of the height of the struts.

26 designates longitudinal bars riveted to the 90 struts 23 at the bottom, there being intermediate horizontal bars 28 riveted to the struts 23 adjacent the rule-joints. Thus the parts 23 to 28 inclusive constitute a frame, (one for the front and one for the back of the receptacle.) 95

In addition to being connected by the front and back frames, the top and bottom rectangular rod-like frames 1 and 6 are also connected at their sides by vertical struts 29 having rule-joints 31 intermediate their ends and having their ends 100 looped around the rods 1 and 6 as at 30.

Suitable stops 32 are welded to the rods 1 and 6 to prevent the struts 29 becoming displaced along those rods, the struts 29 being located in the mid-vertical longitudinal plane of the receptacle. 105

24 is a bag of generally rectangular form set into the skeleton receptacle to rest on the lattice bottom, and this bag 24 has its upper edge overlying the rod-like frame 6 and sewed together. 110

It will be noted that the rule-joints of the several struts break inwardly and it will also be noted that when the front and back frames are folded in and the struts 29 are folded in the end 5 struts will lie between the adjacent rule-joints of the front and back frames. That is to say, the lengths of the sections of the front and back struts are such that when folded inwardly their respective rule-joints will not abut one another 10 but will be spaced apart a distance but slightly greater than the width of the end struts 29.

The bottom of the canvas bag is anchored to the rod-like frame 1 by stitching 27, as best shown in Figure 5.

15 From the foregoing description taken in connection with the accompanying drawing it is thought that the construction, operation and advantages of the invention will be clear to those skilled in the art.

20 What I claim is:

1. In a collapsible receptacle, a top rectangular rod-like rigid frame and a bottom rectangular rod-like rigid frame, a front frame and a back frame, each of said front and back frames consisting of a pair of rule-joint struts located at the ends of the frames and an intermediate rule-joint strut, longitudinal bars rigidly secured to said struts adjacent the top and bottom ends and lying at right angles thereto, said top and bottom 25 ends being bent around said rectangular rod-like frames as hinge loops, and a rule-joint strut for each end of said receptacle connecting the top and bottom rod-like frames in the middle of the end portions, all of said struts breaking inwardly, 30 the distance between the rule-joints and the hinge loops of the struts of the front and back frames being such that when the receptacle is collapsed the rule-joints of the front and back frames will be separated a distance sufficient to receive the 35 folded end struts between them.

2. In a collapsible receptacle, a top rectangular rod-like rigid frame and a bottom rectangular rod-like rigid frame, a front frame and a back frame, each of said front and back frames consisting of a pair of rule-joint struts located at the ends of the frames, and an intermediate rule-joint strut, longitudinal bars rigidly secured to said struts adjacent the top and bottom ends and lying at right angles thereto, said top and bottom 45 ends being bent around said rectangular rod-like frames as hinge loops, and a rule-joint strut for each end of said receptacle connecting the top and bottom rod-like frames in the middle of the end portions, all of said struts breaking inwardly, the 50 distance between the rule-joints and the hinge loops of the struts of the front and back frames being such that when the receptacle is collapsed the rule-joints of the front and back frames will be separated a distance sufficient to receive the folded end struts between them, and a canvas bag 55 fitted within the skeleton receptacle formed by said frames and having its upper edge folded over the upper rectangular rod-like frame and sewed together.

60 3. In a collapsible receptacle, a top rectangular rod-like rigid frame and a bottom rectangular rod-like rigid frame, a front frame and a back frame, each of said front and back frames consisting of a pair of rule-joint struts located at the 65 ends of the frames, and an intermediate rule-joint strut, longitudinal bars rigidly secured to said struts adjacent the top and bottom ends and lying at right angles thereto, said top and bottom 70 ends being bent around said rectangular rod-like frames as hinge loops, and a rule-joint strut for 75

each end of said receptacle connecting the top and bottom rod-like frames in the middle of the end portions, all of said struts breaking inwardly, the distance between the rule-joints and the hinge loops of the struts of the front and back frames 80 being such that when the receptacle is collapsed the rule-joints of the front and back frames will be separated a distance sufficient to receive the folded end struts between them, and a canvas bag fitted within the skeleton receptacle formed by said frames and having its upper edge folded over the upper rectangular rod-like frame and sewed together, and having its bottom anchored to said lower rectangular frame.

4. In a collapsible receptacle, a top rectangular rod-like rigid frame and a bottom rectangular rod-like rigid frame, a front frame and a back frame, each of said front and back frames consisting of a pair of rule-joint struts located at the ends of the frames, and an intermediate rule-joint strut, longitudinal bars rigidly secured to said struts adjacent the top and bottom ends and lying at right angles thereto, said top and bottom 90 ends being bent around said rectangular rod-like frames as hinge loops, and a rule-joint strut for 95 each end of said receptacle connecting the top and bottom rod-like frames in the middle of the end portions, all of said struts breaking inwardly, the distance between the rule-joints and the hinge loops of the struts of the front and back frames 100 being such that when the receptacle is collapsed the rule-joints of the front and back frames will be separated a distance sufficient to receive the folded end struts between them, and a canvas bag 105 fitted within the skeleton receptacle formed by 110 said frames and having its upper edge folded over the upper rectangular rod-like frame and sewed together, and crossed lattice strips secured to said bottom rectangular rod-like frame on which 115 said bag rests.

5. In a collapsible receptacle, a top rectangular rod-like rigid frame and a bottom rectangular rod-like rigid frame, a front frame and a back frame, each of said front and back frames consisting of a pair of rule-joint struts located at 120 the ends of the frames, and an intermediate rule-joint strut, longitudinal bars rigidly secured to said struts adjacent the top and bottom ends and lying at right angles thereto, said top and bottom 125 ends being bent around said rectangular rod-like frames as hinge loops, and a rule-joint strut for each end of said receptacle connecting the top and bottom rod-like frames in the middle of the end portions, all of said struts breaking inwardly, the distance between the rule-joints and 130 the hinge loops of the struts of the front and back frames being such that when the receptacle is collapsed the rule-joints of the front and back frames will be separated a distance sufficient to receive the folded end struts between them, and a canvas bag 135 fitted within the skeleton receptacle formed by said frames and having its upper edge folded over the upper rectangular rod-like frame and sewed together, and having its bottom anchored to said lower rectangular frame, and crossed lattice strips secured to said bottom rectangular rod-like frame on which said bag rests.

6. In a collapsible receptacle, a top rectangular rod-like rigid frame and a bottom rectangular rod-like rigid frame, a front frame and a back frame, each of said front and back frames consisting of a pair of rule-joint struts located at the 140 ends of the frames, and an intermediate rule-joint strut, longitudinal bars rigidly secured to said struts adjacent the top and bottom ends and 145

- lying at right angles thereto, said top and bottom ends being bent around said rectangular rod-like frames as hinge loops, and a rule-joint strut for each end of said receptacle connecting the top 5 and bottom rod-like frames in the middle of the end portions, all of said struts breaking inwardly, the distance between the rule-joints and the hinge loops of the struts of the front and back frames being such that when the receptacle is collapsed 10 the rule-joints of the front and back frames will be separated a distance sufficient to receive the folded end struts between them, and a lid comprising a rectangular rod-like frame with lattice strips secured thereto and a canvas cover on its 15 under face, the edges of which cover are carried back over the frame and stitched together, means hinging said lid to said top rectangular rod-like frame, said top rectangular rod-like frame and said lid frame having apertured padlock receiving lips cooperating with one another. 20
8. In a collapsible receptacle, a top rectangular rod-like rigid frame and a bottom rectangular rod-like rigid frame, a front frame and a back frame, each of said front and back frames consisting of a 25 pair of rule-joint struts located at the ends of the frames, and an intermediate rule-joint strut, longitudinal bars rigidly secured to said struts adjacent the top and bottom ends and lying at right angles thereto, said top and bottom ends being bent around said rectangular rod-like frames as 30 hinge loops, and a rule-joint strut for each end of said receptacle connecting the top and bottom rod-like frames in the middle of the end portions, all of said struts breaking inwardly, the distance 35 between the rule-joints and the hinge loops of the struts of the front and back frames being such that when the receptacle is collapsed the rule-joints of the front and back frames will be separated a distance sufficient to receive the folded 40 end struts between them, and a canvas bag fitted within the skeleton receptacle formed by said frames and having its upper edge folded over the upper rectangular rod-like frame and sewed together, and a lid comprising a rectangular rod- 45
- like frame with lattice strips secured thereto and a canvas cover on its under face, the edges of which cover are carried back over the frame and stitched together, means hinging said lid to said top rectangular rod-like frame, said top rectangular rod-like frame and said lid frame having apertured padlock receiving lips cooperating with one another. 80
9. In a collapsible receptacle, a top rectangular rod-like rigid frame and a bottom rectangular rod-like rigid frame, a front frame and a back frame, each of said front and back frames consisting of a pair of rule-joint struts located at the ends of the frames, and an intermediate rule-joint strut, longitudinal bars rigidly secured to said struts adjacent the top and bottom ends and lying at right angles thereto, said top and bottom ends being bent around said rectangular rod-like frames as hinge loops, and a rule-joint strut for each end of said receptacle connecting the top and bottom rod-like frames in the middle of the end portions, all of said struts breaking inwardly, the distance between the rule-joints and the hinge loops of the struts of the front and back frames being such that when the receptacle is collapsed 100 the rule-joints of the front and back frames will be separated a distance sufficient to receive the folded end struts between them, and a canvas bag fitted within the skeleton receptacle formed by said frames and having its upper edge folded over the upper rectangular rod-like frame and sewed together, and crossed lattice strips secured to said bottom rectangular rod-like frame on which said bag rests, and a lid comprising a rectangular rod-like frame with lattice strips secured thereto and a canvas cover on its under face, the edges of which cover are carried back over the frame and stitched together, means hinging said lid to said top rectangular rod-like frame, said top rectangular rod-like frame and said lid frame having apertured padlock receiving lips cooperating with one another. 105
